[57] CLAIM

The ornamental design for a hand held metal detector,
as shown.

DESCRIPTION

FIG. 1 is a side elevational view of a hand held metal detector showing my new design, with the opposite side being a mirror image, and with the broken line showing for illustrative purpose only and forming no part of the claimed design;

FIG. 2 is a top view;

FIG. 3 is a front view;

FIG. 4 is a back view;

FIG. 5 is a bottom view; and,

FIG. 6 is a perspective view as seen from the top, front
and left side.

FIG. 2

FIG. 1

FIG. 3

FIG. 4

FIG. 5

FIG. 6
